UNITED STATES PATENT OFFICE.

EDWARD CRISPIN, OF CHICAGO, ILLINOIS.

ORNAMENTAL WORK AND PROCESS OF MAKING SAME.

SPECIFICATION forming part of Letters Patent No. 529,782, dated November 27, 1894.

Application filed January 16, 1893. Serial No. 458,603. (No model.)

To all whom it may concern:

Be it known that I, EDWARD CRISPIN, a citizen of the United States, residing at Chicago, in the county of Cook and State of Illinois, have invented a certain new and useful Improvement in Ornamental Work and Processes of Making Same, of which the following is a specification.

My invention relates to the preparation of ornamental work for the walls and ceilings of rooms, cars, and other like uses.

A prominent object of my invention is to provide such ornamental work with a backing consisting of an exceedingly thin and flexible sheet which serves as a means for holding and connecting together the separated relief portions of the work, and for furnishing a back-ground for the same, whereby I attain various marked advantages and desirable results as hereinafter more fully set forth.

In the accompanying drawings,—Figure 1 is a face view of a sheet of ornamental work understood to have been prepared in accordance with my invention, and Fig. 2 is a section 25 through the same on the line $x-x$, Fig. 1.

In carrying out my invention I back the relief portion of the work with some thin foaminous or open mesh fabric, and incorporate within such fabric a portion of the material 30 employed for forming ornamental work, in sufficient quantity for filling its meshes or interstices, and to such end, surplus material is removed from the back-ground portion of the flexible sheet. In this way I provide the relief with a backing or ground sheet composed of exceedingly thin and flexible material, which can be bent without injury. This also permits me to prepare sheets of ornamental work which can be safely transported, 35 and which can be applied to walls and ceilings as readily as ordinary wall paper. A further feature involved in the foregoing is that owing to the extreme thinness of the ground sheet, the latter can when desired, be cut away at 40 points around an ornamental figure in relief, and thereupon the remaining portion of the sheet, which affords an attaching base of suitable area, can be applied as an isolated piece to a ceiling without rendering the line of 45 depression between the ground sheet and the ceiling practically apparent, and in this way, 50 the ornamental work can be applied in patches

at isolated points without necessitating the use of a ground sheet of sufficient area to cover the entire wall or ceiling.

55

In practice I place and spread the material of which the ornament is to be made, while in a fluid or semi-fluid condition upon a mold or matrix, so as to fill the depressions which form the relief A, and leave a thin layer upon the ground portion of the matrix, and preparatory to so doing, I oil the mold or matrix in order that the work will not stick to it. I then place upon the material thus distributed, a thin sheet B, of some suitable open work 65 mesh fabric such as tarleton, or mosquito-netting or the like, and smooth down the fabric by passing or drawing with suitable pressure a scraper or trowel over the fabric, taking care to move the scraper or trowel diagonally 70 with relation to the lines of thread, and to incline it forwardly, so as to avoid wrinkling or otherwise disarranging the light and delicate fabric employed. This operation is performed so as to smooth down the fabric and 75 permit the material upon the ground portion of the matrix to enter and fill the meshes of the same, and at the same time to scrape and thereby remove from the ground or back-ground portion of the sheet, substantially all 80 material over and above the quantity embedded within the meshes of the portion of the fabric which is intended for said ground portion. I also prefer to tamp or further depress the portions of the fabric which directly 85 back the relief so as to form depressions or indentations which can be subsequently filled with material and thereby provide a more secure connection between the relief and the fabric. I then permit the material to set or 90 harden, and as a matter of further improvement I then spread upon the back of the fabric a second layer of the material, slightly thicker than the first, so as to fill such depressions as may have been made by tamping the 95 back of the relief as aforesaid and also completely fill any and all of such portions of the meshes or interstices in the fabric as may be open for such filling. I also level off this second layer with a scraper or trowel and in 100 so doing scrape from the back of the ground portion of the fabric all material except such as is incorporated in the same. While the material placed in the first instance upon the

ground portion of the mold or matrix serves to fill the meshes of the fabric and thus provide a thin flexible ground sheet which also serves to connect separate portions of the relief in a design or figure, I find that during the operation of passing the scraper over the fabric so as to force the material within its meshes and remove all surplus material, the threads of the fabric are apt to be agitated to an extent to prevent secure or perfect union between the fabric and all portions of the material distributed within its meshes, and that in order to more positively fix the material which has been distributed within the meshes of the fabric, it is best to further distribute the material by a second application as aforesaid, so as to fill all cracks or interstices which may have been left as a result of the first treatment. After this second fixing material has been properly distributed, and all surplus scraped from the back of the fabric, the material thus last applied is also allowed to set or harden, after which the mold or matrix can be inverted and raised from the work. The sheet of ornamental work thus prepared can be used without further treatment, although I prefer sizing or treating it with a solution of oil, turpentine and beeswax by dipping it into the same so as to render the flexible sheet tougher, stronger, and more durable. I may however use other suitable sizing or dressing solutions or compositions, such as dextrine, or glue size, varnish, or the like. Sheets of ornamental work thus prepared can be readily attached to walls and ceilings, either flat or curved, and said sheets can be applied either over the entire wall or ceiling surface, or at separate points thereon as may be desired. These sheets of ornamental work can also be painted or colored either prior to or after their application to the surface to be ornamented, and any suitable paste can be employed for securing them to walls, ceilings or the like.

I do not confine myself to any particular material for forming the ornamental portion of the work, and I may use either plaster of paris, pulp, or any other material or composition suitable for such ornamental work, observing that where I employ plaster of paris I prefer mixing in some suitable fiber, for example asbestos fiber. The material for the relief and the material for filling the ground portion of the flexible foraminous or open work sheet may be the same, or may differ, as may be desired, and where I apply a second treatment as aforesaid, I may use a like or different material as preferred, it being observed however that the simplest way is to employ one material throughout. As explanatory therefore of the term "molding-material" as employed in my claims herein, it is expressly understood that the same comprehends any substance either composite or simple, which is adapted for ornamental work such as herein referred to, and capable of being molded to form the relief, or molded

within the pores, interstices or meshes of the thin foraminous or open mesh sheet, or both, and that the said term molding material is not employed in the sense of material used for making molds or matrices. Said material may for the purposes of its application be in either a plastic or semi-fluid condition, according to its nature and capacity for ready set. Thus for example I may use plaster of paris in a condition where it is of about the consistency of cream, it being understood however that the very nature of the work herein described requires that the molding material must at the start have a sufficient degree of fluidity, first to permit it to readily enter and in effect saturate the fabric, that is to say, enter and fill the meshes or interstices of the same, and secondly, to permit the surplus material to be scraped from the delicate fabric without wrinkling or otherwise disturbing the latter. It may therefore be properly said, that in accordance with my invention, the molding material which forms the relief and fills the meshes of the fabric, is cast, in contradistinction to other modes of forming ornamental work in which a layer of molding material is formed upon a flexible backing sheet and given an ornamental surface by pressure either in a mold or between rollers, neither of which operations are suitable for preparing ornamental work in accordance with my invention.

What I claim as my invention is—

1. The process of producing sheets of ornamental work, consisting in spreading the molding material in a semi-fluid or proximately semi-fluid condition upon a matrix, applying thereon a backing sheet of open mesh fabric, incorporating the molding material within such sheet, and removing the molding material from the surface of the ground portions of such backing sheet, substantially as described.

2. The process of producing sheets of ornamental work, consisting in spreading the molding material in a semi-fluid or proximately semi-fluid condition upon a matrix, applying thereon a backing sheet of open mesh fabric, incorporating the molding material within such sheet, removing the molding material from the surface of the ground portions of the sheet and after the material has set, making a second application of molding material to the back of the sheet in quantity sufficient to fill such openings or interstices as may be present as a result of the setting of the first application and thereby fix the same, substantially as described.

3. The process of producing ornamental work, consisting in spreading the molding material upon a matrix, applying thereon a sheet of open mesh material, incorporating the molding material within the sheet, tamping or depressing the sheet in the relief portions of the work, and filling the depressions thus made in the sheet with molding material, substantially as described.

4. Sheet ornamental work comprising a thin flexible sheet of open mesh material provided with and constituting a backing for the relief portions of the work, the ground portions of the sheet being saturated with the molding material but having such material removed from the surface portions thereof, substantially as described.

5. Sheet ornamental work comprising a thin flexible sheet of open mesh material provided with and constituting a backing for

the relief portions of the work, the ground portions of the sheet being saturated with the molding material and portions of the sheet backing the relief being tamped or depressed therein and having the depressions thus formed in the sheet filled with molding material, substantially as described. 15
